UNITED STATES PATENT OFFICE.

ALBERT W. OVERHISER, OF CASCO, MICHIGAN.

SCREENING DEVICE FOR SPRAY-PUMPS.

No. 880,240.

Specification of Letters Patent.

Patented Feb. 25, 1908.

Application filed July 19, 1907. Serial No. 384,596.

To all whom it may concern:

Be it known that I, ALBERT W. OVERHISER, a citizen of the United States, residing in the township of Casco, county of Allegan, State of Michigan, have invented certain new and useful Improvements in Screening Devices for Spray-Pumps, of which the following is a specification.

This invention relates to improvements in pumps.

It relates particularly to improvements in screening devices for spray pumps.

In spraying trees and plants, such as fruit trees for San José scale and the like, the spraying mixture usually contains a large amount of sediment which is likely to clog the suction pipe of the pump or the spray nozzle.

It is the main object of this invention to provide an improved straining or screening device for use on spray pumps and the like by which the clogging of the suction pipe of the pump is prevented, and also a screening device which is automatically cleaned or freed from sediment by the operation of the pump.

Further objects and objects relating to details of construction will definitely appear from the detailed description to follow.

I accomplish the objects of my invention by the devices and means described in the following specification.

The invention is clearly defined and pointed out in the claims.

A structure embodying the features of my invention is clearly illustrated in the accompanying drawing, forming a part of this specification, in which,

Figure 1 is a conventional view of a pump showing the relation of my improved screening device thereto; Fig. 2 is a side elevation of a structure embodying the features of my invention; Fig. 3 is an end elevation thereof; Fig. 4 is a detail longitudinal section therethrough taken on a line corresponding to line 3-3 of Fig. 3; and Fig. 5 is an enlarged detail taken on a line corresponding to line 4-4 of Fig. 3, showing the supporting legs of the strainer.

In the drawings similar reference characters refer to similar parts throughout the several views, and the sectional views are taken looking in the direction of the little arrows at the ends of the section lines.

Referring to the drawings, 1 represents a

pump, the same being shown in conventional form. This pump is of the type having a suction pipe as 2 and a return pipe as 3, the return pipe being designed to deliver into the tank containing the spraying solution, thereby keeping the solution properly agitated.

My improved screening or spraying device preferably consists of a block 4 having pipe openings 5 and 6 therethrough adapted to receive the ends of the suction and return pipes respectively. The block 4 is supported on suitable legs as 7, these legs being preferably formed of wire bent into loop form, as illustrated in Fig. 3, the ends of the wire being inserted into the blocks for securing the legs thereto. See Fig. 5. On the under side of the block 1 secure a screen 8 forming a screening or straining chamber. This screen is preferably formed of a piece of wire net or screen folded to form a chamber, the block 4 forming the top thereof. The screen is secured to the block preferably by means of a band 9 wrapped about the same and secured to the block by means of nails or brads 10. This construction is a very economical one and at the same time is found to be entirely satisfactory in practice. The pipe openings 5 and 6 are preferably arranged through the block so that the return pipe 3 delivers at an angle across the mouth of the suction pipe and also at an angle across the bottom of the screening chamber. This prevents the collection of sediment at the mouth of the suction pipe, as at each stroke of the pump a portion of the charge is delivered back into the pump and also by delivering at an angle to the bottom of the screen chamber frees the same from obstructions. This arrangement also insures the proper agitation of the spraying solution at the mouth of the suction tube.

It will be obvious that my improved screening or straining device is very simple in construction and at the same time it is highly effective for the purpose for which it is designed.

I have illustrated and described the same in detail in the form preferred by me on account of its structural simplicity. I am, however, aware that it is capable of very great variation in structural details without departing from my invention, and I desire to be understood as claiming the same broadly as well as specifically, as illustrated.

Having thus described my invention, what

I claim as new and desire to secure by Letters Patent is:

1. The combination with a pump, of a suction and return pipe therefor; a strainer comprising a block having a pair of pipe openings therethrough in which said suction and return pipes are arranged; supporting legs for said block, and a screen secured to said block to form a screening chamber on the under side thereof, said pipe openings of said block being arranged at an angle to each other so that the said return pipe delivers into the screening chamber across the mouth of the suction pipe and at an angle to the bottom of the screening chamber.
2. The combination with a pump, of a suction and return pipe therefor; a strainer comprising a block having a pair of pipe openings therethrough in which said suction and return pipes are arranged; and a screen secured to said block to form a screening chamber on the under side thereof, said pipe openings of said block being arranged at an angle to each other so that the said return pipe delivers into the screening chamber across the mouth of the suction pipe and at an angle to the bottom of the screening chamber.
3. The combination with a pump, of a suction and return pipe therefor; a strainer comprising a block having a pair of pipe openings therethrough in which said suction and return pipes are arranged; supporting legs for said block, and a screen secured to said block to form a screening chamber on the under side thereof, said pipe openings of said block being arranged at an angle to each other so that the said return pipe delivers into the screening chamber across the mouth of the suction pipe.
4. The combination with a pump, of a suction and return pipe therefor; a strainer comprising a block having a pair of pipe openings therethrough in which said suction and return pipes are arranged; and a screen secured to said block to form a screening chamber

ber on the under side thereof, said pipe openings of said block being arranged at an angle to each other so that the said return pipe delivers into the screening chamber across the mouth of the suction pipe.

50

5. The combination with a pump, of a suction and return pipe therefor; a strainer comprising a block having a pair of pipe openings therethrough in which the said suction and return pipes are arranged; supporting legs for said block, and a screen secured to said block to form a screening chamber.

55

6. The combination with a pump, of a suction and return pipe therefor; a strainer comprising a block having a pair of pipe openings therethrough in which said suction and return pipes are arranged, and a screen secured to said block to form a screening chamber.

60

7. The combination with a pump, of a suction and a return pipe therefor; a screening chamber to which said suction and return pipes are connected, so that the said return pipe delivers into the screening chamber across the mouth of the suction pipe and at an angle to the bottom of the screening chamber.

70

8. The combination with a pump, of a suction and a return pipe therefor; a screening chamber to which said suction and return pipes are connected, so that the said return pipe delivers into the screening chamber across the mouth of the suction pipe.

75

9. The combination with a pump of a suction and return pipe therefor; a strainer to which said suction and return pipe are connected, comprising a screen, said return pipe being arranged to deliver to said screen at an angle thereto.

80

In witness whereof, I have hereunto set my hand and seal in the presence of two witnesses.

85
